FOUNTAIN PEN

Jon Gregg, New Hope, Pa.

Application October 10, 1944, Serial No. 557,957

14 Claims. (Cl. 120—43)

1

This invention relates to fountain pen.

An object of this invention is to provide a fountain pen employing a paste-like writing substance and comprising a barrel provided with a worm rotatably mounted therein, said worm being adapted to be rotated from the rear of the instrument to press the writing substance to the writing point of the instrument.

Another object of this invention is to provide a writing instrument of the character described provided with a ball point and means to press writing medium to the point.

Still another object of this invention is to provide a writing instrument of the character described provided with means slidably mounted thereon to cover the writing point when the instrument is not in use, said covering means being retractable to expose the writing point for writing.

A still further object of this invention is to provide a writing instrument of the character described having a writing head which may be unscrewed from the barrel, and a collapsible refill tube containing writing substance which may then be screwed onto the barrel and the writing substance pressed into the barrel. The tube may then be unscrewed from the barrel and the writing head rescrewed onto the barrel.

Yet another object of this invention is to provide a writing instrument of the character described comprising a barrel, a tubular liner within the barrel, a worm rotatably mounted in the barrel and contacting the liner, and means to turn the worm within the barrel, the barrel, the tubular liner, and its turning means being removable as a unit from the rear end of the barrel, and replaceable therein, whereby to permit a new unit containing an additional supply of writing medium to be replaced within the barrel.

Yet a further object of this invention is to provide a writing instrument of the character described comprising a barrel provided with an inner liner of compressible material and a worm within said barrel pressing against said liner to prevent leakage around the worm blade.

A still further object of this invention is to provide in a writing instrument of the character described, means to permit turning of the worm only in the direction for feeding writing substance to the writing point of the instrument.

Yet another object of this invention is to provide a strong, durable and compact writing instrument of the character described which shall be relatively inexpensive to manufacture, easy to

2

manipulate and refill, and which shall be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an axial cross-sectional view of a writing instrument embodying the invention;

Fig. 2 is a partial view of the writing instrument with the closure means retracted to expose the writing point;

Fig. 3 is a cross-sectional view taken on line 3—3 of Fig. 2;

Fig. 4 is a cross-sectional view taken on line 4—4 of Fig. 1;

Fig. 5 is a view similar to Fig. 2 but illustrating a modified construction;

Fig. 6 is a front end view of a fountain pen embodying the invention and still further modified;

Fig. 7 is a top plan view of a modified form of retainer for the writing point of the instrument;

Fig. 8 is a view similar to Fig. 5 and illustrating yet another form of the invention;

Fig. 9 is a front end view of the structure shown in Fig. 8;

Fig. 10 is a side view of the structure shown in Fig. 8 with the closure cap retracted; and

Fig. 11 is a top plan view, partially in cross-section, of the writing instrument with the writing head removed and a refill tube screwed onto the barrel.

Referring now in detail to the drawing, 10 designates a writing instrument embodying the invention. The same comprises a cylindrical barrel 11 having an externally screw threaded portion 11a at its rear end forming a shoulder 11b. At its front end the barrel 11 is formed with an internal screw threaded portion 13 forming a recessed inner shoulder 14.

In the drawing the reduced end edge of barrel 11 is designated by numeral 11c. Screwed onto the rear end of the barrel is a rear end member 11d. Member 11d is formed with an internally screw threaded portion 11e adapted to be screwed to the screw threaded portion 11a of the barrel. The forward end 11f of member 11d contacts shoulder 11b of the barrel. Member 11d is fur-

thermore, formed with a shoulder 11g opposite the end 11c of the barrel.

Interposed between surfaces 11c and 11g is a washer 11h. Member 11d is formed with a through opening 12. At its rear surface it is also formed with an annular internal groove 23 for the purpose hereinafter appearing. Member 11d is also formed with an inner cylindrical surface 11i coextensive with the inner surface 11k of the barrel 11.

Within the barrel 11 is a tubular or cylindrical liner 15 made of rubber or compressible synthetic material. The liner 15 extends from the shoulder 14 and contacts surfaces 11k and 11j. The tube 15 fits snugly within the barrel.

Within the tube 15 is a worm 16 having a worm blade 17 pressed against the inner surface of tube 15. At the rear end of the worm is a cylindrical head 18 and extending therefrom is a stem 19 passing through the opening 12. Stem 19 is formed with a reduced ratchet portion 20 disposed beyond the rear surface of the barrel 11, and with a further reduced screw threaded end portion 21 beyond the ratchet. In the annular groove 23 is a washer or gasket 24 surrounding stem 19 to prevent leakage through said opening 12. Surrounding said stem 19 is also a washer 23a contacting the inner surface of member 11d. Screwed onto the screw threaded portion 21 is a head, cap or handle 25. Said cap 25 is formed with a recess 26 on its underside and with a screw threaded opening 27 extending from the recess to receive the screw 21. The stem 19 is preferably formed with a shoulder 28 contacting the bottom wall of recess 26 so that the cap 25 will not be wedged tight against the barrel. The end surface 25a of cap 25 presses washer 24 to seal opening 12 when said cap contacts shoulder 28. It will now be understood that upon turning the cap, the worm 16 will be turned therewith.

Fixed to the rear end of the barrel is a pivot pin 30 and pivoted thereon is a pawl 31 engaging the ratchet teeth 20. A suitable spring 32 serves to press the pawl 31 against the ratchet 20 so that the worm can only be turned in a direction for feeding writing substance downwardly in the barrel toward the writing point, as will appear more fully hereinafter.

Screwed onto the barrel 11 is a writing head 40. The writing head 40 comprises a tubular member 41 having an external screw threaded portion 42 screwed into the screw threaded portion 13 of the barrel. The screw threaded portion 42 has an end surface 44 contacting shoulder 14 and also contacting the forward end of tube 15, thereby retaining said tube within the barrel. Member 41 is furthermore formed with a tapered through opening 45. At its forward end it is formed with a shank 41a having an externally screw threaded front end portion 46 forming an external, recessed shoulder 47. Member 41 is also formed with an annular groove 48 at the rear end of shank 41a, spaced from shoulder 47, for the purpose hereinafter appearing. It is also formed with a cylindrical axial groove 49 extending rearwardly of shank 41a. Screwed onto screw threaded portion 46 of member 41, and contacting shoulder 47, is a tip 50. The tip 50 is formed with an internally screw threaded portion 51 engaging the threaded portion 46. It is formed with a forwardly and inwardly curved wall 52, and has a central opening 53 at the front end thereof. Wall 52 has outer and inner curved surfaces 52a, 52b extending to the rim edge 51 at opening 53. On the forward end of

tube 41 is a ball retainer 55. The same may be made of spring wire and is in the form of a key-hole shaped loop having a substantially elliptical central portion 56 and U-shaped end portions 57. The end portions 57 rest on shoulder 41b at the front end of member 41.

Mounted on portion 56 of the spring 55 is a ball 60. The spring serves to press the ball against the rim 57 of member 50 at the opening 53. The writing medium employed in the pen is in paste form. The same may be in the form of an ink or a graphite composition or any other suitable writing medium.

Upon turning the handle 25 the writing medium 15 will be pressed forwardly through passage 45 and past spring 55 into the chamber 65 formed between the ball 60 and the shoulder 41b. As a person writes with the instrument, the ball 60 will rotate and carry writing medium around so as to provide a supply of writing substance to the ball point. It will be noted that the worm can only be rotated in a direction for feeding writing medium toward the ball point.

Means is provided to enclose the writing point, said means being retractable to expose said point. To this end there is mounted on the head 41 a tubular member 70 having a cylindrical portion 71 surrounding portion 41a of the tube 41, and projecting into the cylindrical groove 49. The forward end 71a of member 70 is tapered to a point and is formed with radiating slits 72 thereby providing a plurality of segments 73 which may be spread open. On the rear end of member 50 is an external annular rib 74 engaging the inner surfaces of the segments 73. Between the segments 73 and the cylindrical wall 71 is an inwardly extending annular rib 75 forming an annular external groove 76. Within said groove is a split ring 77. It will now be understood that when member 70 is pressed forwardly the segments 73 close up to cover the writing point as shown in Fig. 1 of the drawing. When member 70 is retracted the segments 73 are opened up by the annular rib 74, and the cylindrical portion 71 is received within the groove 49. The rib 75 of member 70 may snap into the groove 49 to retain member 70 in retracted position, as shown in Fig. 2 of the drawing.

50 The writing instrument may be refilled with writing substance by unscrewing the head 41, and screwing onto the barrel, in its place, a refill tube 80. The refill tube 80 may be of the collapsible type and is provided with a screw threaded neck 81 which may screw into the screw threaded portion 13 of the barrel. After the tube is screwed onto the barrel, the tube is collapsed or pressed, to squeeze or press the contents into the barrel. After the barrel is refilled with writing substance the tube 80 may be unscrewed therefrom and the writing head 40 rescrewed onto the barrel.

It will be understood that by unscrewing member 11d from the barrel, the worm member 25 and the tube can be removed as a unit from the barrel. Another unit filled with writing substance may then be replaced into the barrel, thereby serving as a refill for writing medium. The liner tube 15 serves as a container for the writing medium. The front end of the tube may be closed by any suitable capping material which may be removed prior to insertion into the barrel.

If desired, furthermore, member 11d may be 75 made integral with the barrel as one piece and

in such event the inner liner tube 15 as well as the worm may be inserted through the front end of the barrel. With such construction the refilling would be accomplished by means of the refill tube 80 as illustrated in Fig. 11.

In Fig. 5 there is shown a pen 10a illustrating a modified construction. Pen 10a is similar to pen 10 with the exception that the ball 60 is replaced by an ellipsoid shaped writing point 90. The writing point 90 may be held in place by a spring retainer 55 or by an annular plate formed with a central opening 92 and resting on shoulder 41b. The rear end of writing point 90 partially projects into the opening 92. The writing point is formed with a plurality of longitudinal grooves 93 through which the writing medium may pass to the front end of the point. The groove preferably terminates short of the front end of the writing point.

In Fig. 6 there is shown a pen 10b illustrating another modified form of the invention. The pen 10b is similar to pen 10a except that it is provided with an ellipsoid shaped writing point 95 which has no grooves. The pen is provided with a member 50a similar to member 50 except that at the opening it is formed with a plurality of small notches 96 to permit writing medium to pass through to the forward end of the writing point 95.

In Fig. 7 there is shown a washer 97 to replace the spring 55. Washer 97 has an annular flat plate formed with a central opening 97a on which the ball 60 rests. The writing medium may pass through openings 98 in the washer, to the point.

In Figs. 8, 9 and 10 there is shown a pen 10c illustrating yet another form of the invention. The pen 10c is the same as the pen 10 with the exception that there is substituted for the closure means 70 a modified closure means 100. The closure means 100 comprises a tube 101 at the front end of which is a diaphragm. The diaphragm 102 has radial slits 103 to form segments 104. The diaphragm may be fixed to the front end of the tube in any suitable manner. Tube 101 is provided with an inwardly extending annular rib 105. The rib 105 contacts rib 74 to prevent the closure means from coming off the pen. Also rib 105 may snap into the annular groove 48 to retain the closure means in retracted position. The rear end of the tube 100 may be formed with longitudinal slits 106 so that the tube will have resiliency at the rib 105. When the tube 100 is retracted the segments 104 open up and the ball passes therethrough so it is exposed for the writing operation. The rear end of tube 101 enters the groove 49 when the tube is retracted.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A writing instrument comprising a barrel, a worm within the barrel, said writing instrument having a nib, and a paste-like writing substance within the barrel adapted to be pressed towards

the nib upon turning the worm within the barrel.

2. A writing instrument comprising a barrel, a worm within the barrel, said writing instrument having a nib, a paste-like writing substance adapted to be pressed toward the nib upon turning the worm within the barrel, and a tubular liner of compressible material within the barrel and contacted by the worm.

3. A writing instrument comprising a barrel, a worm within the barrel, said writing instrument having a nib, a tubular liner of compressible material within the barrel and contacted by the worm, and means at the rear end of the barrel to turn said worm.

4. A pen comprising a barrel, a tubular liner within the barrel, a worm within the barrel and contacting said liner, and a writing head screwed to the barrel and retaining said tube in said barrel.

5. A pen comprising a barrel, a tubular liner within the barrel, a worm within the barrel and contacting said liner, a writing head screwed to the barrel and retaining said tube in said barrel, and a ball point at the forward end of the writing head.

6. A pen comprising a barrel, a tubular liner within the barrel, a worm within the barrel and contacting said liner, a writing head screwed to the barrel and retaining said tube in said barrel, a ball point at the forward end of the writing head, and means at the rear end of the barrel and connected to the worm for turning the worm within the barrel.

7. A pen comprising a barrel a paste-like writing substance within the barrel, a tubular liner within the barrel, a worm within the barrel and contacting said liner, a writing head screwed to the barrel and retaining said tube in said barrel, a ball point at the forward end of the writing head, means at the rear end of the barrel and connected to the worm for turning the worm within the barrel, and means to prevent rotation of the barrel in a direction to force this writing substance back from the ball point.

8. A pen comprising a barrel a paste like writing substance within the barrel, a worm within the barrel, a writing head at the front end of the barrel, a ball point at the front end of the writing head, a worm within said barrel, and means at the rear end of the barrel to rotate the worm.

9. A pen comprising a barrel a paste like writing substance within the barrel, a worm within the barrel, a writing head at the front end of the barrel a ball point at the front end of the writing head, a worm within said barrel, means at the rear end of the barrel to rotate the worm, and a paste-like writing substance within the barrel adapted to be pressed toward the writing point upon turning said worm within said barrel.

10. A pen comprising a barrel a paste like writing substance within the barrel, said barrel having an internally screw threaded portion at the front end, and a rear wall at its rear end, a worm within said barrel, a stem at the rear end of said worm, said rear wall having a through opening, through which said stem passes, a member fixed to said stem for turning said worm, a tubular writing head having external screw threads screwed to the screw threaded portion of said barrel, an annular tip member screwed to the forward end of said writing head, said tip member being curved forwardly and inwardly and being formed with a central opening, a ball within said tip member, and means within the tip mem-

70
75

ber to retain the ball at the opening in said tip member.

11. A pen comprising a barrel a paste like writing substance within the barrel, said barrel having an internally screw threaded portion at the front end, and a rear wall at its rear end, a worm within said barrel, a stem at the rear end of said worm, said rear wall having a through opening, through which said stem passes, a member fixed to said stem for turning said worm, a tubular writing head having external screw threads screwed to the screw threaded portion of said barrel, an annular tip member screwed to the forward end of said writing head, said tip member being curved forwardly and inwardly and being formed with a central opening, a ball within said tip member, means within the tip member to retain the ball at the opening in said tip member, and a tubular liner within said barrel contacting the worm, said writing head having means to contact the tubular liner to retain the same within said barrel.

12. A pen comprising a barrel a paste like

writing substance within the barrel, a worm therein, a writing head attached to the barrel, a tip member attached to the forward end of the writing head, said tip member being formed with a central opening at its front end, a writing point within said tip member, and means to retain the writing point partially projected through said opening.

13. A pen comprising a barrel a paste like writing substance within the barrel, a member attached to the rear end of the barrel, a worm within the barrel, and rotatably mounted on said member, and means on said member to rotate the worm within the barrel.

14. A pen comprising a barrel a paste like writing substance within the barrel, a member attached to the rear end of the barrel, a worm within the barrel, and rotatably mounted on said member, means on said member to rotate the worm within the barrel, a writing head attached to the front end of the barrel, and a writing point at the front end of said writing head.

JON GREGG.
